UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

CLOCKING ATTACHMENT FOR CIRCULAR-KNITTING MACHINES.

1,081,254.

Specification of Letters Patent.

Patented Dec. 9, 1913.

Application filed May 20, 1912. Serial No. 698,360.

To all whom it may concern:

Be it known that I, FRANK W. ROBINSON, a citizen of the United States, and a resident of the city of Reading, in the county of Berks and State of Pennsylvania, have invented certain new and useful Improvements in Clocking Attachments for Circular-Knitting Machines, of which the following is a specification.

10 My invention relates to circular knitting machines, and consists particularly in an improved mechanism attachable thereto for controlling the engagement of additional threads upon certain of the needles as required to produce clock ornamentation upon the opposite sides of stockings.

The invention is fully described in connection with the accompanying drawings illustrating a preferred embodiment thereof, and 20 the novel features are clearly pointed out in the subjoined claims.

Figure 1 is a sectional elevation of my improved mechanism complete, indicating also its arrangement relative to the usual needle cylinder and cam cylinder; the section being taken on the line 1—1 of Fig. 2. Fig. 2 is a plan view of the same. Fig. 3 is a separate sectional view of the combined cam rings; and Figs. 4 and 5 are respectively top and bottom views of the same. Fig. 6 is a separate sectional view of the inner non-rotatable ring, with its attached shaft brackets for carrying the adjustable stop mechanism; the removably secured bottom retaining-ring portion thereof being shown as slightly separated from the main portion. Figs. 7 and 8 are respectively top and bottom views of the main portion of said inner ring, and Fig. 9 is a top view of said removably secured retaining-ring portion thereof. Fig. 10 is a plan view of the cam-operated thread-carrier bars and spring-controlled arms; the bar-contacting faces of the respective cams, and the bar-engaging stops of the frame ring, being indicated in dotted lines. Fig. 11 is a cross-sectional view on the line 11—11 of Fig. 2. Figs. 12, 13, 14, 15 and 16 are detail views, and Fig. 17 indicates a simple product of my improved mechanism.

50 In Fig. 1 the knitting needles of an ordinary circular knitting machine are indicated at 2, the usual rotary cam cylinder at 3, and a pattern chain such as is frequently employed, at 4.

My improved mechanism is carried on the 55 main frame of the machine, as indicated, by means of suitable vertical brackets, 5 and 6 respectively; and the required motions are derived from the cam cylinder by contact of an ordinary part 7 thereof with a depending 60 forked-arm 8 of my attached mechanism, and from the pattern chain 4 through a suitable lug-engaging lever 9, as hereinafter fully described. The main elements of the attached mechanism are the thread fingers 65 10, 10, and the general purpose of my improved mechanism is to provide for passing these fingers between needles on opposite sides of the needle cylinder, and for imparting a regulated swinging movement to them, 70 so as to engage the threads carried thereby upon any determined number of needles and thereby work into the opposite sides of the fabric which is being knitted, the desired clock ornamentation. 75

My clocking mechanism is mounted, as shown, upon a frame-ring 15, which is provided with a hinge-arm 16 pivoted to one of the standards at 17, and with an oppositely extending arm 18 adapted to seat upon the 80 other standard 6 when the mechanism is in normal working position over the needle cylinder. A counterbalance weight 19 is arranged to automatically raise the hinged frame-ring and its attached mechanism out 85 of working position when a locking latch 20 is released.

The forked arm 8 which is engaged by the cam cylinder of the machine, is attached to a cam-ring 25 which is rotatably carried 90 upon a circular ledge 28 on the interior of the frame-ring 15. For convenient assembling, this cam-ring is built up of separately formed parts though operated as a single device, as indicated in Fig. 3; the top cam-segment 26 being fixed to the upper surface of the main ring portion 25, and the bottom cam-ring 27, to which the forked arm 8 is secured, being fixed to the lower surface of the same. The whole device turns freely in 100 the frame-ring 15, the circular inner wall of which completes the top cam face 26^a; and the top and bottom cam-faces, 26^a and 27^a (Fig. 10), contact respectively with the ends of the thread-carrier bars 35 and 36 which 105 are arranged at right-angles and one above the other, within the cam-ring 25.

The longitudinal movement of the main

- thread-carrier bar 35 is arranged to carry the thread-fingers 10, 10, in and out between the knitting needles 2; while the right-angled movement of the bar 36 effects the swing of the fingers for engaging the threads thereof upon the needles. The means for controlling these movements and for regulating the extent of the needle-engaging swing will now be described.
- 10 Though the cam-ring device 25—26—27, is freely rotated in the fixed frame-ring 15, it carries upon an interior circular ledge 29 thereof, an inner non-rotating ring 45 in which the bars 35 and 36 are held. The 15 lower retaining plate 46 of this inner ring (see Figs. 6 and 9) is removably secured to it, beneath the lower bar 36; which latter is moved diametrically in recessed ways 47, 47 (Fig. 8), by contact of its ends with the rotary cam-face 27^a. The upper bar 35 is moved diametrically, at right-angles to bar 36, in similar recessed ways 48, 48 (Fig. 7), by contact of its ends with the rotary cam-face 26^a; said ends being also arranged to engage 20 successively, during the latter part of the reverse movements, in notches 51, 51 of oppositely arranged locking plates 52, 52 on the frame-ring 15. This engagement of the bar 36 in one or other of the fixed locking 25 plates 52, serves to at all times prevent the inner ring 45 from partaking of the rotary movement of the cam-ring 25 on which it is supported, the bar being also engaged in the recessed ways 48 of the ring as previously 30 described. As already stated, the reverse movements of the bar 35 carry the thread fingers 10, 10 in and out between the needles. These fingers however are not directly secured to the bar 35, but are respectively fixed 35 to the free ends of thread-arms 60, 60 which have a common pivotal connection 61 to said bar; and these pivoted arms are connected to the other cam-operated bar 36, by means of springs 62, 62, 62, 62 as shown, so 40 that the movement of said bar 36 at right-angles to that of bar 35 will exert a pull upon said pivoted arms, through the springs 62, which tends to swing the fingers crosswise of the needles and of the bar 35; such 45 swing being adapted to engage the threads upon certain of the needles preliminary to each reversal of the movement of the bar 35. The extent of this swing, and the corresponding number of needles engaged by the 50 thread at each inward movement of the thread-fingers, is controlled by the pattern-chain 4 through a stop mechanism for said pivoted thread-arms which is carried by the non-rotating inner ring 45.
- 55 The swing of the pivoted thread-arms 60 crosswise of the bar 35, is directly controlled by a pair of vertically slideable stops 70, the forked ends of which (see Fig. 14) may be shaped as required to effect any desired 60 variation of the swing by correspondingly

varying the vertical position of the stop relative to the plane in which the thread-arms swing.

The stop mechanism, as shown, is carried upon the non-rotating inner-ring 45, upon the upper face of which are secured vertical brackets 71, 71. In these brackets is mounted a shaft 72 having fixed thereto a pair of stepped adjusting-cams 73, 73, the faces of which contact with shoulders 74 on the stops to hold the latter in more or less lowered position against the action of lifting springs 75. The stops are vertically guided in ways 76 formed in the ring 45 (see Fig. 7). One end of the shaft 72 is provided with a star wheel 80, and in one of the shaft brackets is mounted a spring-pressed locking pin 88 which engages recesses in the shaft corresponding with the teeth of said wheel. The latter is turned by the operating cam-ring 25, as determined by the pattern chain 4, to vary the position of the stops 70 as desired for successive courses; and this turning of the star wheel 80 and stop-operating shaft 72, is effected by means of a tooth-engaging pin or pins 81 mounted in a vertical pin-bracket 82 carried by the cam-ring 25; said pins being spring-retracted horizontally in their bearing lugs 83 on said bracket, so as to normally hold their inner ends in a path outside of the star wheel, but being forcibly moved inward to engage and turn said wheel, by means controlled by the pattern chain 4. As shown, two pins 81 are provided, arranged one above the other so as to engage the star wheel teeth respectively above and below its center and thus permit of its being turned either backward or forward. The projection of the pins to engage the star wheel is effected by a contacting disk 85, which is mounted in the frame-ring arm 16 so as to be moved vertically by a lever 9^a which swings with the lever 9 as determined by lugs 86, 87 on the pattern chain 4; these lugs being adapted to raise it into the path of either the lower or upper pin 81 as desired, so that the desired pin will be projected inwardly as they are carried past the disk with the rotary cam-ring 25. When thus projected the pin 81 is in each case held by a spring-depressed latch 90 which descends into a notch 91 of the pin, and is so held until said latch is raised by contact of its depending stem 90^a with a cam-lever 92. This lever 92, which is pivoted to the frame-ring arm 16 adjacent the disk 85, is swung into the path of the latch stems 90^a by the descent of said disk into its inoperative position (Figs. 1 and 2), but is moved out of this path by a spring 93 whenever the disk is raised by a pattern-chain lug.

The clocking threads are suitably guided from their bobbins to the fingers 10.

The entire attachment may be thrown away from the knitting machine by raising

the pivoted frame-ring 15, but when the latter is lowered to operative position as shown, the rotation of the cam cylinder 3 of the machine carries with it the cam-ring 25 of the attachment, and the cam faces 26^a 27^a of said ring contact with the ends of the thread-carrier bars 35, 36 so as to impart to the latter, fixed reciprocating movements at right angles to each other. Each movement 10 of the main bar 35 carries the fingers between adjacent needles of the needle cylinder, one inwardly and the other outwardly. The forked ends of the stops 70 are so shaped that when the latter are fully lowered by a 15 corresponding setting of the cams 73, on shaft 72, the pivoted finger arms on bar 35 will be held thereby so as to be unaffected by the crosswise movement of the other bar 36, which movement in such case merely varies 20 the tension of the springs 62 without swinging the fingers so as to engage their threads upon any needle; but when said stops 70 are more or less raised, by determined operation of the shaft 72 as described, a corresponding 25 swing of the fingers will be effected by the movement of the bar 36 before the movement of the bar 35 returns the fingers between other needles, so that the clocking threads will be worked upon the fabric by 30 the engaged needles. The relative length and movement of the bar 35 is such that while one end or other thereof is always engaged in the fixed locking plates 52 so as to prevent rotation of the inner-ring 45 with 35 the cam-ring 25 as required, there will be sufficient space between each end successively, and the adjacent fixed plates 52, to permit the vertical bracket 82 of the rotary cam-ring 25 to pass.

40 Fig. 17 shows a product with clock ornamentation of simple design, which, it will be noticed, is so arranged as to satisfactorily clear the heel point 100 of the stocking in proceeding continuously along the sides of 45 the leg and foot portions. It is merely to effect this purpose that certain parts of the attachment are shown as out of center sufficiently to keep clear of that half of the needles which is used in forming the heel.

50 The specific construction shown and described may obviously be modified without departing from the invention, and the clock or stripe embroidery provided for may be readily varied in design and location.

55 What I claim is:—

1. A clocking attachment for circular knitting machines comprising a fixed frame-ring, a rotary cam-ring supported thereby, and coöperating thread-finger bars diametrically mounted within said cam-ring at right-angles to each other and reciprocatively operated by the latter to respectively carry the thread between and crosswise of the needles substantially as set forth.

65 2. A clocking attachment for circular

knitting machines comprising a fixed frame-ring, a rotary cam-ring supported thereby, a non-rotatable inner-ring, and coöperating thread-finger bars guided in said inner-ring at right-angles to each other and reciprocatively operated by said cam-ring to respectively carry the thread between and crosswise of the needles substantially as set forth. 70

3. A clocking attachment for circular 75 knitting machines comprising a fixed frame-ring, a rotary cam-ring supported thereby, an inner-ring supported by said rotary cam-ring, and coöperating thread-finger bars guided in said inner-ring at right angles to each other and reciprocatively operated by said cam-ring to respectively carry the thread between and crosswise of the needles, and fixed locking-devices adapted to be respectively engaged by the ends of one of 80 said reciprocating bars so as to prevent rotation of said inner-ring. 85

4. In a clocking attachment for circular knitting machines comprising a fixed frame-ring and a rotary cam-ring; thread-finger 90 bars diametrically mounted within said cam-ring at right-angles to each other and adapted to be reciprocatively operated by the latter, and thread-finger arms carried by one of said reciprocating bars and capable of 95 lateral movement thereon; said arms being operatively connected to the other bar.

5. In a clocking attachment for circular knitting machines comprising a fixed frame-ring and a rotary cam-ring; thread-finger 100 bars diametrically mounted within said cam-ring at right-angles to each other and adapted to be reciprocatively operated by the latter, thread-finger arms carried by one of said reciprocating bars and capable of lateral movement thereon, spring connections 105 between said arms and the other bar, and stop devices for limiting the lateral movement of said arms.

6. In a clocking attachment for circular 110 knitting machines comprising a fixed frame-ring and a rotary cam-ring; thread-finger bars diametrically mounted within said cam-ring at right-angles to each other and adapted to be reciprocatively operated by the latter, thread-finger arms carried by one of said reciprocating bars and capable of lateral movement thereon, spring connection between said arms and the other bar, and adjustable stop devices for variably limiting 115 the lateral movement of said arms. 120

7. In a clocking attachment for circular knitting machines comprising a fixed frame-ring, a rotary cam-ring, a non-rotatable inner-ring, thread-finger bars reciprocatively 125 guided in said inner-ring at right angles to each other, and laterally movable thread-finger arms carried by one of said reciprocating bars and having spring connections to the other bar; vertically movable stop de- 130

4

vices for engaging said arms, a cam shaft for adjusting said stop devices, and means carried by said rotary cam-ring for intermittently turning said cam shaft.

- 5 8. In a clocking attachment for circular knitting machines comprising a fixed frame-ring, a rotary cam-ring, a non-rotatable inner ring, thread-finger bars reciprocatively guided in said inner-ring at right-angles to
10 each other, and laterally movable thread-finger arms carried by one of said reciprocating bars and having spring connections to the other bar; vertically movable stop de-

vices for engaging said arms, a cam shaft for adjusting said devices, an adjustable-¹⁵ pin mechanism carried by said rotary cam-ring for operating said shaft, and pin-adjusting means adapted to be thrown into or out of the path of said pin mechanism.

In testimony whereof, I affix my signature, in the presence of two witnesses.

FRANK W. ROBINSON.
